UNITED STATES PATENT OFFICE.

CHARLES C. PRESGRAVES AND WILLIAM L. GOLDEN, OF HAGERSTOWN, MARYLAND.

SIGNAL.

Application filed May 22, 1920. Serial No. 383,525.

To all whom it may concern:

Be it known that we, CHARLES C. PRESGRAVES and WILLIAM L. GOLDEN, citizens of the United States, residing at Hagerstown, 5 in the county of Washington, and State of Maryland, have invented certain new and useful Improvements in Signals, of which the following is a specification.

This invention relates to certain improvements in signals and has relation more particularly to a device of this general character which is electrically operated, and it is an object of the invention to provide a novel and improved device of this general 15 character adapted for use in connection with a vehicle and which device is under speed control.

Another object of the invention is to provide a novel and improved device of this 20 general character which operates to give both a visual and an audible signal, said visual and audible signals being independently operable at certain speeds.

An additional object of the invention is to 25 provide a novel and improved device of this general character which operates upon an excessive speed to give an alarm and which alarm can only be caused to stop operation by an authorized person such as a 30 police officer or the like, and which alarm also continues to operate even though the speed be reduced.

The invention consists in the details of 35 construction and in the combination and arrangement of the several parts of our improved signal whereby certain important advantages are attained and the device rendered simpler, less expensive and otherwise more convenient and advantageous for use, 40 as will be hereinafter more fully set forth.

The novel features of our invention will hereinafter be definitely claimed.

In order that our invention may be the better understood, we will now proceed to 45 describe the same with reference to the accompanying drawings, wherein:

Figure 1 is a view partly in vertical section and partly in elevation illustrating a signal constructed in accordance with an embodiment of our invention and in applied position, the coacting portion of an automobile body being diagrammatically indicated by dotted lines.

Figure 2 is a fragmentary view partly in 55 section and partly in elevation showing the door of the casing in closed position.

Figure 3 is a fragmentary view partly in rear elevation and partly in section of the base member coacting with the pointer arbor, illustrating certain details of the invention 60 as herein embodied.

Figure 4 is a view in front elevation of the raised portion of the base illustrating in detail the contacts with which coacts the member carried by the pointer arbor. 65

Figure 5 is a view in elevation of the dial.

Figure 6 is an enlarged fragmentary sectional view illustrating in detail the circuit closer herein included open. 70

Figure 7 is a view similar to Figure 6 showing said circuit closer closed.

Figure 8 is an enlarged fragmentary view partly in elevation and partly in section illustrating the visual signalling means herein 75 embodied.

Figure 9 is a view in bottom plan of the structure illustrated in Figure 8 showing the brushes and coacting contacts for operating the lamp, and 80

Figure 10 is a diagrammatic view of our improved signal.

As disclosed in the accompanying drawings, C denotes a casing adapted to be positioned within the cowl of an automobile body 85 or the like with a face thereof comprised in the dash D.

One end of the casing C is open and is adapted to close by the door A. The door A is maintained closed through the medium 90 of a conventional key-operated latch mechanism L. In practice, a key for operating the latch mechanism L is kept in possession by the police department or other officials having supervision over vehicular traffic, so 95 that access within the casing C cannot be had by unauthorized persons.

S denotes a speedometer of a conventional type having its dial 1 exposed through the dash D for visual access and wherein the 100 pointer 2 coacting with the dial 1 is mounted upon the arbor or shaft 3. The arbor or shaft 3 extends within the casing C and adapted to be operatively connected in a conventional manner with a drive wheel or 105 other desired moving part of the vehicle so that the rate of speed of the vehicle may be readily ascertained by reading the speedometer in the well known manner.

The speedometer S includes a base portion 4 having its outer face provided with a circular raised portion 5 of a diameter

substantially the same as the diameter of the dial 1 with the periphery of said raised portion 5 concentric to the arbor or shaft 3 which passes therethrough and also through the base 4. The dial 1 is secured to the raised portion 5 through the instrumentality of the screws 6 or the like and said dial overlies said raised portion 5 and is maintained in spaced relation thereto through the medium of the outstanding spacing elements 7 carried by the marginal part of said raised portion 5.

The raised portion 5 is provided with an outstanding arcuate rib or bead 8 leading from a point in coincidence with the "0" indication on the dial D to the "12" indication or other indication in accordance with the traffic regulations of a municipality as to the maximum speed. The rib or bead 8 is continued by an arcuate contact member 9 terminating at the "35" indication or other indication of the maximum speed limit in open country. The contact member 9 is continued by a relatively short rib or bead 10 of insulating material as is also the rib or bead 8. The rib or bead 10 is continued by an arcuate contact member 11 leading from the "38" indication or other indication slightly beyond the maximum speed indication for open country. The contact member 11 is continued by the arcuate rib or bead 12 of insulating material.

The arbor or shaft 3 is of metal and in electrical contact therewith between the raised portion 5 and the dial 1 is an elongated contact member 14 movable therewith and having its end portion engaging the ribs or beads 8, 10 and 12 or the contact members 9 and 11, dependent upon the speed of the vehicle as indicated by the pointer 2. The arm or contact member 14 is also preferably in parallelism with the pointer 2.

The rear face of the base 4 is provided with a pocket or chamber 15 and disposed across said pocket or chamber 15 and secured as at 16 to the inner wall thereof is a conductor plate 17 in electrical connection with the arbor or shaft 3 and which contact is further facilitated by a disk 18 fixed to the arbor or shaft 3 inwardly of the contact plate 17 and constantly in contact with said plate.

The marginal portion of the rear face of the base 4 is provided with four outstanding binding posts *a*, *b*, *c* and *d* and the post *a* is in electrical connection with the plate 17 through the instrumentality of the conductor *a'*.

The high end of the contact member 9 extends through the base 4 into the pocket or chamber 15 and is in electrical connection through the conductor *d'* with the post *d*.

The high end of the contact member 11

also extends through the base 4 into the pocket or chamber 15 and said extended portion is in electrical connection through the medium of the conductor *b'* with the post *b*. The portion of the contact member 11 70 within the recess or chamber 15 is also formed into a contact 19 spaced from the inner face or base of the pocket or chamber 15. Coacting with the contact 19 is an angular extension 20 of a contact member 75 21 and which extension is positioned between said contact 19 and the inner face or base of the pocket or chamber 15. The contact member 21 extends outwardly through the base 4 at a point inwardly of 80 and in substantially radial alignment with the contact 11 and the outer end portion of said contact 21 is secured to an arm 22. The opposite end portion of the arm 22 is engaged with the raised portion 5 and in 85 a manner whereby the same may be forced inwardly by contact of the contact member or arm 14 as the same passes thereover. The member or arm 14 operates to force the contact 21 inwardly substantially at the 90 time the contact arm or member passes from the contact 11 upon the adjacent end of the rib or bead 12. When the contact 21 is forced inwardly the extension 20 thereof is brought into electrical engagement with the contact 19 and such contact 19 is maintained until the contact 21 is manually moved outwardly to separate the extension 20 and contact 19.

The contact 21 is in electrical connection with the arm and the end portion of said arm 22 secured to the raised portion 5 is in electrical connection through the medium of the conductor *c'* of the binding post *c*.

E denotes a source of electrical energy which may comprise a series of dry cells arranged within the casing C or other source of electrical energy as may best meet with the requirements of practice.

Supported by the outer side face of the casing C and arranged within said casing is a motor M having the axis of its armature vertically disposed and rotating with said armature is a vertically disposed cylindrical member 23. The upper end of the member 23 is continued by a tubular cylindrical member 24 of transparent material and having disposed therearound on a spiral 115 bands 25 of desired color and translucent.

Extending upwardly from the member 23 and axially of the member 24 is a post 26 provided at its upper end with an electric lamp or bulb 27. Leading from the contacts of the lamp or bulb 27 are the conductors *e*, one of said conductors being in electrical connection with an annular contact member 28 carried by the end or bottom surface of the member 23 and the sec- 120 125 130

ond conductor *e* being in electrical connection with the continuous contact band extending circumferentially around the lower portion of the member 23. The top wall 5 of the casing C is provided with a depending block 29 provided with brushes 30 and 31, the brush 30 being in electrical connection with the contact member 28 and the brush 31 being in electrical connection with 10 the contact member 28'.

The base of the casing C is provided with a pair of upstanding posts 32 and 33 in suitable electrical connection with the source E by the conductors *f* and *g* coacting respectively with the posts 32 and 33. The post 32 is in electrical connection through the conductor *h* with the post *a* and with the post *c* through the conductor *k*. Leading from the post *b* is a conductor *n* in electrical connection with a contact member 34 arranged on the bottom or floor of the casing C adjacent the open end thereof.

A post 35 of the motor M is in electrical connection through the conductor *o* with the post *d* and said post 35 is in electrical connection with the brush 31 through the conductor *m*. The second post 36 of the motor is in electrical connection through the conductor *o'* with the post 33 and said post 33 is also in electrical connection through the conductor *p* with the brush 30 hereinbefore referred to. The post 36 is also in electrical connection through the conductor *n'* with a second contact member 34' carried by the 35 bottom of the casing C adjacent the open end thereof.

Secured to the inner face of the door A is an electrically operated bell B of a conventional type and which embodies the contact 40 points 37 and 37' and which posts engage respectively the contacts 34 and 34' when the door is closed.

When the vehicle is running at a speed below twelve miles, our improved signal is 45 operative, but when the arm or contact member 14 engages the contact 9, the motor circuit is closed, resulting in a rotation of the member 23 and at the same time the circuit for the lamp or bulb 27 is closed, whereby 50 the rotating member 24 and the rays emitted from the lamp or bulb 27 give a visual signal that the vehicle is traveling at a speed in excess of the limit of speed within a municipality or the like. Upon an increase of speed 55 of the vehicle, the contact member or arm 14 will engage the contact 11, whereby the motor circuit and the lamp circuit will be broken and the circuit for the bell B closed, so that an audible signal will be given so that 60 the driver of the vehicle may know that he is exceeding the speed limit in the open country or county.

Upon still further increase in speed beyond this last limit of speed, say about two 65 miles, the contact member or arm will en-

gage the contact 11 and at the same time force the contact 21 inwardly to cause the extension 20 thereof to have electrical connection with the contact 19. The bell circuit is closed and cannot be reopened until after 70 access has been had within the casing C to manually separate the extension 20 from the contact 19.

The key for the locking mechanism L is not in the possession of the driver of the vehicle 75 but is adapted to be in the possession of the police officials or other parties having control of traffic, so that in the event the vehicle should travel beyond the extreme limit of speed as provided by the regulations, the 80 same will be readily made known to the proper officials by the ringing of the bell B even though the speed of the car be reduced because the bell circuit is closed and can only be reopened from within the casing C. 85 In view of this fact, the continued ringing of the bell B clearly indicates that the driver of the car has broken the traffic laws or regulations and is, therefore, subject to arrest.

In order to effect the requisite separation 90 of the extension 20 of the contact 21 and the contact 19, we find it of advantage to arrange within the casing C an elongated member or rod 39 supported for endwise movement and having one end terminating in close proximity to the inner end of the contact 21 or the extension 20 thereof. Coacting with the rod 39 is an expansible member or spring 40 which serves to constantly urge the rod 39 in a direction away from the contact 21 or the 100 extension 20 thereof. Upon opening the door A, it is only necessary to move the rod 39 in a direction toward the base 4 and which movement results in the rod 39 forcing the contact member 21 outwardly and disengaging the extension 20 thereof from the contact 19.

The member 23 extends exteriorly of the casing C through an opening 41 in the top thereof and the member 24 is housed within 110 a cylindrical casing 42 of glass or other transparent material. The top of the casing 42 is closed by a cap 43 or the like preferably of opaque material and the inner face of said cap is provided with a reflecting 115 medium 44 preferably a mirror so that the efficiency of the lamp or bulb 27 and particularly after nightfall is materially increased.

The casing 42 is carried by and extends 120 above a block 45. The block 45 is suitably secured to the top wall of the casing C and in a manner whereby said block 45, together with the casing 42, closes or seals the opening 41.

The casing 42 extends upwardly above the lower portion of the windshield of an automobile or the like and interposed between said casing and the windshield is a plate 46 extending upwardly from the block 45, said 130

plate terminating above the casing 42 and of a width greater than the width of said casing. The plate 46 is provided with a restricted sight opening 47 whereby the driver 5 or other occupant of the car may have visual access to the rotating member 24 and as facilitated by the burning lamp or bulb 27.

Our improved signal also provides means, and particularly through the instrumentality of the bell B, to notify the passengers within the rear portion of the vehicle that the speed limit is being exceeded and this is of especial importance in connection with private cars driven by a chauffeur.

15 It is also manifest that the device can be used to considerable advantage in delivering cars from the factory to the purchaser or to the local agent in a distant city. By the use of this device the manufacturer can keep tab 20 on the road record of the driver of the car from the factory to the city where the car is to be sold and the dealer or purchaser when he receives the car at his end of the line can immediately determine whether at any time 25 along the route the driver of the car has exceeded the maximum predetermined speed limit for which the device is set at the factory. In this way, the driver of the car will be prevented from speeding the car and 30 from entailing the damage and wear that result from excessive speeding.

From the foregoing description it is thought to be obvious that a signal constructed in accordance with our invention is 35 particularly well adapted for use by reason of the convenience and facility with which it may be assembled and operated, and it will also be obvious that our invention is susceptible of some change and modification 40 without departing from the principles and spirit thereof and for this reason we do not wish to be understood as limiting ourselves to the precise arrangement and formation of the several parts herein shown in carrying 45 out our invention in practice except as hereinafter claimed.

We claim:

1. The combination with the pointer arbor of a speedometer, an electrically operated 50 visual signal including a normally open cir-

cuit, an electrically operated audible signal including two operating circuits each normally open, one of said last named circuits including a circuit closer movable by pressure into either open or closed position, and 55 a member movable with the pointer arbor, said member in one position closing the circuit for the visual signal, closing one of the circuits of the audible signal when in a second position, and closing the pressure-operated circuit closer when in a third position.

2. The combination with the pointer arbor of a speedometer, an electrically operated visual signal including a normally open circuit, an electrically operated audible signal 60 including two operating circuits each normally open, one of said last named circuits including a circuit closer movable by pressure into either open or closed position, a member movable with the pointer arbor, 70 said member in one position closing the circuit for the visual signal, closing one of the circuits of the audible signal when in a second position, and closing the pressure-operated circuit closer when in a third position, 75 and means operable independently of said member for opening the pressure-operated circuit closer.

3. The combination with the pointer arbor of a speedometer, an electrically operated 80 visual signal including a normally open circuit, an electrically operated audible signal including two operating circuits each normally open, one of said last named circuits including a circuit closer movable by pressure 85 into either open or closed position, a member movable with the pointer arbor, said member in one position closing the circuit for the visual signal, closing one of the circuits of the audible signal when in a second position, and closing the pressure-operated circuit closer when in a third position, 90 means operable independently of said member for opening the pressure-operated circuit closer, and means for preventing access to 95 said last named means.

In testimony whereof we affix our signatures.

CHARLES C. PRESGRAVES.
WILLIAM L. GOLDEN.
